UNITED STATES PATENT OFFICE

FRANS O. ALBERTSON, OF SIOUX CITY, IOWA, ASSIGNOR TO ALBERTSON & COMPANY, INC., OF SIOUX CITY, IOWA, A CORPORATION OF IOWA

DESIGN FOR A CASING FOR A PORTABLE ELECTRIC POLISHER

Application filed August 13, 1932. Serial No. 44,598. Term of patent 14 years.

To all whom it may concern:

Be it known that I, FRANS O. ALBERTSON, a citizen of the United States, residing at Sioux City, in the county of Woodbury and State of Iowa, have invented a new, original, and ornamental Design for a Casing for a Portable Electric Polisher, of which the following is a specification, reference being had to the accompanying drawing, forming part thereof.

Fig. 1 is a plan view of a casing for a portable electric polisher showing my new design; and

Fig. 2 is a perspective view of the same.

I claim:

The ornamental design for a casing for a portable electric polisher as shown.

In witness whereof, I hereunto subscribe my name, this 9 day of August, 1932.

FRANS O. ALBERTSON.
